UNITED STATES PATENT OFFICE.

ERNEST S. HENSON, OF SYRACUSE, NEW YORK.

DISPENSER.

Application filed May 12, 1924. Serial No. 712,690.

This invention relates to improvements in dispensing devices particularly adapted for the use of sugar and like commodities.

An important object of the invention is 5 to provide a dispensing device for sugar or like commodities which may dispense the commodities without material opening thereof.

A further object of the invention is to 10 provide a device of this character which will retain the sugar or other commodity free from dust or other particles at all times.

A still further object of the invention is to 15 provide a dispensing device of this character which is comparatively simple in construction, durable and efficient for the purpose intended.

Other objects and advantages of this invention will be apparent during the course 20 of the following description.

In the accompanying drawings forming a part of this specification and in which like numerals are employed to designate like parts throughout the same:

25 Figure 1 is a front elevation of the assembled device embodying my invention.

Figure 2 is a horizontal section taken on the line 2—2 of Figure 1.

30 Figure 3 is a vertical section taken on the line 3—3 of Figure 1.

Figure 4 is a top plan view of one of the sections.

Figure 5 is a perspective view of the top plate,

35 Figure 6 is a perspective view of the operating member,

Figure 7 is a front elevation of a modified form of my invention,

40 Figure 8 is a horizontal section taken on the line 8—8 of Figure 7, and

Figure 9 is a vertical section taken on the line 9—9 of Figure 8.

In the drawings, wherein for the purpose of illustration is shown the preferred embodiment of my invention, the numeral 10 generally denotes the body structure of my improved dispenser having a container 11 constructed of glass or other desirable material secured thereon, the same being held in 45 place by a plurality of connecting strips 12 attached to the container 11 and body member 10. The container or bowl 11 is preferably provided with a conical partition 13 tapering downwardly toward the center 50 of the bowl and having an opening. The 55

lower portion of the body 10 has a plurality of supporting legs 14 secured thereto and adapted to retain the device in position.

The body portion 10 is composed of a plurality of sections, the bottom or base 60 section 15 having a rectangular recess 16 formed in the upper side, an angular groove 17 connecting with the recess 16 and extending to the front of the section. The front portion of the groove 17 connects 65 with an enlarged recess 18 adapted to receive a pulley 19 rotatably mounted therein. A like pulley 20 is positioned at the angular intersection of the groove 17 and is vertically pivoted to the base. 70

An intermediate section 21 is positioned upon the base section 15 and supports the top plate 22 which is also provided with a rectangular opening 23 on the bottom side. 75

In order to provide a dispensing channel 80 through the dispenser body, the top plate 22 has a circular opening 24 formed therein, the said opening being aligned with a pair of cylindrical tubes 25 mounted within the base and intermediate sections. A square cam shaft 26 is vertically mounted through suitable openings in the body section adjacent the dispensing channel and retained in position by a pair of washers 27 and nuts 28 threadedly mounted upon the extremities 85 of the cam shaft 26. A cam plate 29 is connected to the cam shaft 26 and adapted to swing within the recess 23 formed in the top plate, thus closing and opening the dispensing channel. A similar cam 30 is 90 mounted within the lower recess 16 and likewise mounted upon the cam shaft, the two cam plates being firmly positioned upon the cam shaft in order that one plate covers the dispensing channel when the other plate is 95 swung away. A quadrant 31 is also connected to the cam shaft and preferably positioned in the lower recess 16 providing means for rotating the cam shaft and cam plates. A tension spring 32 is secured to one side of the quadrant 31 and to the base section 15 forcing the quadrant to one side of the section and yieldably holding the upper cam plate 29 in closed position and the lower cam plate 30 in open position. 100 An operating cord or wire 33 is secured to the other side of the quadrant 31, positioned about the pulleys and connected to a finger clip 34 formed on the upper portion of a reciprocating lug 35. 105 110

The lug 35 and the finger clip formed thereon are adapted to vertically reciprocate within a suitable guide 36 secured to the base section 15 and forming the operating means for dispensing the commodity through the channel. A curved spout 37 is secured to the lower portion of the base 15 in alignment with the dispensing channel and adapted to discharge the sugar or other commodity into a receptacle.

In the modified form of my invention shown in Figures 7, 8 and 9, the body portion denoted by the numeral 38 is composed of one section and has a horizontal partition plate 39 secured on the inside slightly above the bottom. A cylindrical dispensing tube 40 is vertically positioned within the body and secured to the top plate 41 and partition plate 39, the bottom 42 of the body being provided with a circular opening 42' in direct alignment with the dispensing tube channel. A dispensing spout 43 is secured to the bottom plate 42 immediately surrounding the opening 42' formed therein and is intended to divert the flow of sugar or other commodities into the receptacle. A cam shaft 44 is vertically pivoted through the body 38 adjacent the dispensing tube 40, the upper extremity of the cam shaft, which is preferably square in cross section, carries a swinging cam plate 45 which is actuated by the cam shaft and covers and uncovers the tube 40, depending on the movement imparted to the cam shaft. A similar cam plate 46 is mounted near the lower extremity of the cam shaft 44 and is positioned between the bottom casing plate 42 and the partition plate 39, the lower cam plate being mounted upon the shaft 44 at a suitable angular displacement in relation to the upper cam plate to permit one of the plates to cover the opening of the vertical tube 40 while the other uncovers the same. An angular actuating rod 47 is also mounted upon the cam shaft 44 at approximately the central portion thereof, the actuating rod 47 extending towards the rear of the casing and prevented from displacement upon the cam shaft by means of cotter pins 48. Mounted upon the side of the casing body 38 is a vertical adjustable hand lever 49 pivoted to the side of the body as at 50 and adapted to swing through a slot 51 formed in the bottom of the body. A connecting wire or cord 52 is secured to the extremity of the actuating rod 47 and passes over a roll pulley 53 rotatably mounted in the front portion of the body. The other extremity of the connecting wire 52 is secured to the operating handle 49 thus causing movement of the actuating rod upon manipulation of the operating handle. In order to cause the actuating bar 47 to return to its normal position I provide a coil tension spring 54, one extremity thereof being se-

cured to the actuating bar and the other extremity fastened to the side of the casing body.

A conventional type of container 55 is positioned upon the casing body 38 and is to be filled with sugar or any other commodity it is desired to dispense. The supporting legs in this form of my invention are composed of angular bars 56 enclosing the corners of the device and adapted to steadily retain same in position. One of the front supporting legs is provided with a vertical slot 57 permitting vertical adjustment of the operating handle 49.

In use, the device is particularly intended for restaurants and the like, where patrons desiring to sweeten a beverage might place the cup containing same beneath the spouts 37 or 43 and actuate the finger clip 34 or operating handle 49 causing the container to discharge a predetermined quantity of sugar into the receptacle. The amount discharged through the dispensing channel at each movement of the clip or handle may be regulated as desired, the size of the dispensing tube in the casing body determining the amount of the commodity dispensed at each operation. It is considered advisable to insert a tube retaining an amount equal to a teaspoonful as this is usually the minimum amount used for sweetening beverages. It is further to be noted that the dispenser is closed at all times and the accumulation of dust or other undesirable matter with the commodity being dispensed is thus entirely eliminated forming a highly serviceable and sanitary dispenser.

It is to be understood that the form of my invention herewith shown and described is to be taken as the preferred example of the same, and that various changes as to the shape, size and arrangement of parts may be resorted to without departing from the spirit of the invention, or the scope of the subjoined claim.

Having thus described my invention, I claim:

A sugar dispenser comprising a body composed of a plurality of sections, the upper section comprising a top plate having a circular opening formed therein and a rectangular recess on the bottom portion thereof, an intermediate section having a cylindrical tube mounted therein, a base section having a rectangular recess formed in the upper portion and a cylindrical tube, both the said tubes being aligned with the circular opening in the top plate, a square cam shaft rotatably mounted through the body sections, an upper cam plate secured to the cam shaft and adapted to swing within the recess formed in the top plate, a lower cam plate secured to the said cam shaft adapted to swing in the recess formed in the base section, the said cam plates being positioned

upon the cam shaft so that when one is moved to open communication through the dispensing channel, the other is moved to close communication through the dispensing channel, means for retaining the cam shaft in position, a discharge spout secured to the base section in alignment with the dispensing channel therein, a plurality of supporting stanchions secured to the base section, a bowl or container secured to the top plate and having a conical bottom formed therein, a cover positioned on the said container, an operating quadrant secured to the said cam shaft and positioned within the recess formed in the base section, a coil spring secured to the quadrant and base and normally holding said quadrant to one side of the recess, an operating cord secured to the other side of the quadrant and connecting with a finger clip, and means for limiting movement of the said finger clip.

5

10

I testify whereof, I have affixed my signature.

ERNEST S. HENSON.
